X-RAY PROCESSING TANK

John W. Carr, Pacific Palisades, Calif.

Application August 18, 1958, Serial No. 52,247

Term of patent 14 years

(Cl. D61—1)

Fig. 1 is a perspective view of the front and right end of an X-ray processing tank, showing my new design; and Fig. 2 is a side elevational view of the left end thereof on a reduced scale.

The back not shown, is conventional. A part of Fig. 1 is diagonally lined to indicate translucency.

I claim:

The ornamental design for an X-ray processing tank, as shown and described.
